UNITED STATES PATENT OFFICE.

DANIEL A. KEATING, OF BRIDGEPORT, AND JAMES B. TATEM, OF PUTNAM, CONNECTICUT, ASSIGNORS OF ONE-HALF TO THE AMERICAN TUBE & STAMPING COMPANY, OF BRIDGEPORT, CONNECTICUT, A CORPORATION OF CONNECTICUT, AND ONE-HALF TO JAMES B. TATEM, DOING BUSINESS AS JAMES B. TATEM & SON, OF PUTNAM, CONNECTICUT.

PICKER STICK.

Application filed June 19, 1924. Serial No. 720,955.

To all whom it may concern:

Be it known that we, DANIEL A. KEATING and JAMES B. TATEM, citizens of the United States, residing at Bridgeport and Putnam,

5 respectively, in the counties of Fairfield and Windham, respectively, and State of Connecticut, have invented certain new and useful Improvements in Picker Sticks, of which the following is a specification.

10 This invention relates to an improved construction of combined wood and metal picker stick of the type employed for driving the shuttle across a loom; and the object of this invention is to provide a picker stick of this character having its upper portion of wood and its lower portion of metal, the wood providing the necessary resiliency for receiving and throwing the shuttle across the loom while the lower portion provides additional strength to that portion which is usually the first to become broken where an all-wooden stick is employed.

15 A further object of this invention is to form the upper portion of wood and the lower portion of two opposite side plates bolted or otherwise secured to the sides of the wooden portion to simplify construction of this metal portion of the picker stick and at the same time provide greater strength to that portion which ordinarily is the first to break.

20 A still further object of this invention is the provision of a relatively short filler or spacing member for spacing the lower ends of the side plates and to provide a suitable bearing for the pivot pin on which the picker stick may oscillate if it is desired to mount it upon a pin for this purpose.

25 With these and other objects in view, the invention consists of certain novel features of construction, as will be more fully described, and particularly pointed out in the appended claims.

In the accompanying drawings:

30 Figure 1 is a side elevation of our improved picker stick showing the upper portion of wood and the lower portion formed of metal side plates fastened to the wood.

35 Figure 2 is an edge view of our improved construction of picker stick showing the side plates as fastened to the sides of the wooden portion.

40 Figures 3 and 4 show constructions where-

by the opposite side plates are formed of shallow channel members bolted to opposite sides of the wooden portion and having a 55 tubular spacer at their lower ends.

Figure 5 is a section on line 5—5 of Figure 3 showing the end of the wooden member as secured between the side plates.

Figure 6 is a section on line 6—6 of Figure 4, showing a deep flange on one of the side plates providing a backing for the attachment of the operating member.

Figure 7 is a sectional view on line 7—7 of Figure 3, showing a spacer member as 65 formed on a short length of tubing riveted to the opposite side plates.

The operating life of an ordinary wooden picker stick as is well known, is very short. It is also known that a picker stick requires 70 a certain amount of resiliency or spring in order to properly act upon and throw the shuttle across a loom, and, therefore, in order to strengthen that portion of the stick which ordinarily breaks first and at the 75 same time obtain the necessary yieldability, we have formed a picker stick with its upper portion of wood, by which we obtain the necessary elasticity and its lower portion of metal by which we obtain the strength required to withstand the extreme hard usage 80 to which the picker stick is subjected; and the following is a detailed description of one embodiment of our present invention by which these advantageous results may 85 be accomplished.

With reference to the drawings, 10 designates the upper portion of our improved construction of picker stick which is formed of wood, usually hickory, the same being 90 preferably rectangular in cross section, larger at the bottom portion 12 and tapered towards its smaller, upper portion 13.

The lower portion of this stick is herein 95 shown as being formed of two side plates 14 and bolted to the opposite sides of the lower portion of the wooden member 10 by a plurality of bolts or rivets 15, a spacer member 16 being placed between the lower ends of these side plates which may be formed of a block of wood 17 such as lignum vitae or other wood of the necessary hardness to withstand the required strains, or any other suitable material may be employed, and

when such a block is employed it may be secured by means of bolts or rivets 18 or any other suitable means.

In some instances, instead of employing the plain, ordinary side plates 14 for the lower portion of the picker stick, we may form these side plates 19, as illustrated in Figures 3 to 7, inclusive, each with narrow edge flanges 20 which perform the double function of lateral strengthening of the side plates permitting them to be made of thinner material and also providing a support for the front and rear edges of the wooden portion of the stick as at 21 against the thrust or the blow of the shuttle upon it thereby reducing the number of fastening bolts 22 required, over the number required in the construction of peak side plates, illustrated in Figures 1 and 2.

In some instances, instead of the block of wood 16, as illustrated in Figures 1 and 2, to perform the functions of a spacer, we pierce the side plates as at 23 and insert a short length of tubing 24 having a shoulder with extending portion 25 which are swaged, upset, or riveted into chamfered holes in the side plates to securely lock these ends of the plates together and at the same time provide a suitable, continuous bearing between the side plates for the pivot pin on which the picker stick may oscillate.

In some instances, we provide a tapered flange portion 26 on one of the flanged side plates to form a support through which to attach the operating mechanism.

In some instances, we permit the side walls of the side plates to extend beyond the flanged portions 20, whereby a recess is provided for the reception of a return strap (not shown).

We do not wish to be limited to mounting our improved picker stick to oscillate upon a pivot pin as other suitable means for supporting the lower end, may be employed.

Our improved construction of picker stick is extremely simple and inexpensive to manufacture and by its use we provide the necessary resiliency for the throwing of the shuttle and also the necessary strength of that portion of the stick which ordinarily breaks first.

The foregoing description is directed solely towards the construction illustrated, but we desire it to be understood that we reserve the privilege of resorting to all the mechanical changes to which the device is susceptible, the invention being defined and limited only by the terms of the appended claims.

We claim:

1. A picker stick having substantially its upper half of wood and substantially its lower half of two separate lengths of spaced-apart oppositely-disposed metal side plates, said plates being supported in spaced rela-

tion at their opposite ends and disposed in substantially parallel relation throughout their length.

2. A picker stick having substantially its upper half of wood and substantially its lower half formed of two separate lengths of spaced-apart oppositely-disposed substantially parallel metal side plates, the upper ends of said plates being secured to opposite sides of the lower end portion of the wooden member, and a spacer member of substantially the same thickness as that of said upper end member for supporting the lower ends of said plate in spaced relation.

3. A picker stick having substantially its upper half of wood and substantially its lower half of two separate lengths of oppositely-disposed substantially parallel spaced-apart metal side plates, the upper ends of said plates being secured to opposite sides of the lower end portion of the wooden member and having a spacer bearing member secured between their lower ends.

4. A picker stick having substantially its upper half of wood and substantially its lower half formed of two separate lengths of spaced-apart metal side plates with narrow stiffening flanges on their edges along the major portion of their length, and a separate spacer member secured between the lower ends of said plates.

5. A picker stick having substantially its upper half of wood and substantially its lower half of spaced-apart substantially parallel metal plates flanged at their upper ends to closely fit the lower end of said wooden portion, and an independent spacer and bearing member secured between the lower ends of said plates.

6. A picker stick having substantially its upper half of wood and substantially its lower half of spaced-apart substantially parallel metal plates flanged on their edges to engage and support the wooden portion against the thrust of the picker stick.

7. A picker stick having substantially its upper half of wood and substantially its lower half of parallel spaced apart metal plates flanged on their edges to engage and support the wooden portion against the thrust of the picker stick, and a bearing spacer member secured between the lower ends of said plates.

8. A picker stick having substantially its upper half of wood and substantially its lower half formed of a pair of spaced-apart substantially parallel metal plates having their upper ends spaced by and secured to opposite sides of the lower portion of said wooden member and having a spacer block between their lower ends, said plates and spacer having an opening there-through to receive a pivot pin.

9. A picker stick having its upper por-

tion of wood and its lower portion of a pair of metal plates secured to opposite sides of said wooden portion, and a short tubular section between said plates at their lower 5 ends providing a spacer and also a bearing for the pivot pin.

10. A picker stick having its upper portion of wood and its lower portion of a pair of metal plates secured to opposite sides of 10 said wooden portion, and a short tubular section between said plates at their lower ends providing a spacer and also a bearing for the pivot pin, the ends of said tube being riveted to said plates to secure it in position.

15. 11. A picker stick having its upper portion of wood and its lower portion of a pair of metal plates secured to said wooden por-

tion and a short tubular section extending through the lower ends of said plates and shouldered to engage the inner surface of 20 said plate to provide a spacer therefor.

12. A picker stick having its upper portion of wood and its lower portion of a pair of separate metal plates and a short tubular section between said plates at their lower 25 ends for spacing said plates apart, said section having reduced ends extending through said plates and riveted over at their outer ends to secure said plates in spaced relation.

In testimony whereof we affix our signatures.

DANIEL A. KEATING.
JAMES B. TATEM.
